[57] CLAIM

The ornamental design for a gripping, wire fence stretcher connector, as shown and described.

DESCRIPTION

FIG. 1 is a top perspective view of a gripping, wire fence stretcher connector showing my new design;

FIG. 2 is a front elevational view thereof, the rear elevation view being a mirror image with the exception that the circular ring does not have a break;

FIG. 3 is a top plan view thereof;

FIG. 4 is a right side elevational view thereof; and,

FIG. 5 is a left side elevational view thereof.
